E. W. CLARKE,
WATER COOLED SKEWBACK,
APPLICATION FILED NOV. 7, 1916.

1,267,057.

Patented May 21, 1918.

UNITED STATES PATENT OFFICE.

EDGAR W. CLARKE, OF WESTMONT BOROUGH, PENNSYLVANIA.

WATER-COOLED SKEWBACK.

1,267,057.

Specification of Letters Patent. Patented May 21, 1918.

Application filed November 7, 1916. Serial No. 129,979.

To all whom it may concern:

Be it known that I, EDGAR W. CLARKE, a citizen of the United States and a resident of the borough of Westmont, county of Cambria, and State of Pennsylvania, (whose post-office address is Johnstown, Pennsylvania,) have invented certain new and useful Improvements in Water-Cooled Skewbacks; and I do hereby declare the following to be a full, clear, and exact description of the invention, such as will enable others skilled in the art to which it appertains to make and use the same.

My invention relates to the construction of heating, melting or other furnaces, and particularly to those that are provided with arched roofs formed of fire bricks, or other refractory material, and my invention resides in the construction and arrangement of a water cooled skewback for supporting the ends of the arches in place of the customary skewback brick. My water cooled skewback may also be made adjustable in position to accommodate any outline or arrangement of arch desired and it may be supported by the furnace frame-work, the furnace walls or by the buckstays thereof. My water cooled skewback is also preferably made sectional so that the portions thereof may be arranged in any alinement desired and I may connect the cooling pipes of the different sections in such a way that a certain amount of flexibility is provided to allow for contraction and expansion without breaking the skewback, water pipes or connections.

In the specifications and drawings herein I have confined my description and drawings to the use of my skewback in connection with an open-hearth melting furnace for the sake of simplicity, but I wish it understood that it is equally applicable to other furnaces and to those having arched roofs, lintels, or other portions requiring a support of this character.

Having thus given a general description of my invention, I will now, in order to make the matter more clear, refer to the annexed sheet of drawings which forms part of this specification and in which like characters denote like parts:

Figure 1 is a front elevation of the super-structure of one-half of an open-hearth furnace with the upper portions of the regenerators shown in cross section, my cooled

skewback being shown as applied thereto; Fig. 2 is a cross sectional elevation of a furnace taken on the center line II—II of Fig. 1; Fig. 3 is a detailed elevation on an enlarged scale of one section of my water cooled skewback and a portion of the adjacent section showing the pipe connections and hanging bolts; Fig. 4 is an end view of the right-hand end portion of Fig. 3; Fig. 5 is a cross section on the line V—V of Fig. 3, showing a water pipe with the elbow nipple and union removed and a portion of a hanging and adjusting bolt; Fig. 6 is a cross sectional view of the skewback showing another manner of supporting the same upon the frame-work or buckstays of the furnace; Fig. 7 is a cross sectional view of the skewback showing another and slightly modified form of supporting the same; and Fig. 8 shows the skewback with still another slightly different method of support.

Referring now to the various characters of reference on the drawings: 1 represents an open-hearth furnace in general, 2 the arched roof thereof, 3 are my water cooled skewbacks which may be made of cast iron, cast steel or other metal with conduits formed therein to which the cooling pipes 4 are attached or integral therewith, as desired; these cooling pipes having upwardly projecting portions 5 which are connected by means of elbows 6 and unions 7. By means of this construction of upwardly projecting pipes, the alinement of the skewbacks to each other may be varied, as desired, and the flexibility of a joint of this character, on account of its length, will allow for any expansions or contractions of the structure without breaking the pipe connections. As particularly illustrated in Figs. 2, 3, 4 and 5 of the drawings, the skewbacks are adjustably supported by the bolts 8 which pass through an opening 9 provided therefore in the skewback, a recess 10 being also provided to accommodate the lower end of the bolt and a nut thereon, leaving the vertical surface of the skewback free from obstructions. The upper ends of these bolts are supported by angles or projections 11, forming parts of or secured to the buckstays or frame-work of the furnace, and the nuts 12 on the upper ends of the bolts serve to support the skewback and also allow it to be adjusted up and down to the alinement

desired. The furnace buckstays are indicated generally as 13, and the cross tie rods as 14.

For the purpose of clearness of illustration, other portions of the furnace are shown, but are not specifically referred to, as they do not comprise my invention.

Referring now to Fig. 6: the supporting and adjusting bolts 8 are not used in this case, but in place thereof I use the channel 15, the lower flange of which fits within the recess of the skewback, as shown, and supports it by contact of the upper surface of said lower flange with the upper boundary 15 surface of the recess, as illustrated. Referring now to Fig. 7, my skewback is directly supported upon the angle 16 which is secured to the frame-work or buckstays of the furnace and which may be placed in any position desired thereon and secured thereto by bolts or rivets. Another slightly different arrangement of the support of my skewback is shown in Fig. 8, which consists of an angle 17 secured with one leg projecting upwardly and the other inwardly, and on the inwardly projecting leg the skewback rests and is supported, this angle 17 being secured to the buckstays by bolts or rivets in any position, as may be desired. The side walls 80 of the furnace are 18, while the door arch is 19.

On account of the approximately triangular or trapezoidal form of my skewback, a slope is provided on its inner surface so as to properly and directly receive the arch bricks of the roof construction, and these bricks, therefore, may be of the same size and conformation. The cooling feature of my skewback enables it to withstand the high heats to which it may be subjected in use, and in case the furnace walls, door arches or adjacent portions of the brick or refractory structure below the skewbacks should be burned away or become weak in use, the skewback would still be maintained in position, as it is hung upon the bolts 8 or supported directly by the frame-work of the furnace. This is one of the main features of my construction and renders the roof arch 50 independent of the support of the side walls or other portions of the furnace, and it also prevents settlement of the roof, or in case the side walls should shrink or settle slightly owing to heat, the opening occasioned there- 55 by between them and the skewback could be readily closed by refractory material. By reason of the adjustable bolts 8 my skew-

back can be located at any position desired on the furnace and the position may be varied from time to time upon rebuilding if 60 considered expedient or necessary.

Although I have described and illustrated my invention in considerable detail, I do not wish to be limited to the exact and specific details thereof as shown and described, but 65 may use such modifications in, substitutions for, or equivalents thereof, as are embraced within the scope of my invention, or as pointed out in the claims.

Having thus described my invention, what 70 I claim and desire to secure by Letters Patent is:—

1. A furnace skewback comprising a plurality of sections, each provided with a number of connected cooling conduits therein, 75 flexible pipe connections extending from one section to the adjacent section and a flat horizontal bearing surface and a bolt hole connected therewith within the lines of said skewback, a bolt mounted in said hole with 80 its head or nut contiguous to said bearing surface and its body projecting outwardly through said hole, said bolt being adjustably mounted on the inner side of the furnace frame-work. 85

2. A furnace skewback of approximately triangular or trapezoidal section provided with cooling conduits therein, a flat horizontal bearing surface and a bolt hole connected therewith within the lines of said skewback, 90 a bolt mounted in said hole with its head or nut contiguous to said bearing surface and its body projecting outwardly through said hole, said bolt being adjustably mounted on the inner side of the furnace frame-work, 95 and flexible pipes connecting the conduits of one section with those of the adjacent section.

3. A furnace skewback provided with a plurality of conduits therein, cooling fluid 100 connections to said conduits, a flat horizontal bearing surface and a bolt hole connected therewith within the lines of said skewback, a bolt mounted in said hole with its head or nut contiguous to said bearing surface and 105 its body projecting outwardly through said hole, said bolt being adjustably mounted on the inner side of the furnace frame-work, the inner surface of said skewback being sloping and adapted to directly receive the 110 furnace arch bricks.

In testimony whereof I hereunto affix my signature.

EDGAR W. CLARKE.
